UNITED STATES PATENT OFFICE

93,435

DESIGN FOR A MOTOR VEHICLE HEATER CASING OR SIMILAR ARTICLE

Frank Acton, Columbus, Ohio, assignor to Francisco Auto Heater Company, Cleveland, Ohio, a corporation of Ohio

Application July 30, 1934, Serial No. 52,743

Term of patent 3½ years

To all whom it may concern:

Be it known that I, FRANK ACTON, a citizen of the United States, residing at Columbus, in the county of Franklin and State of Ohio, have invented a new, original, and ornamental Design for a Motor Vehicle Heater Casing or Similar Article, of which the following is a specification, reference being had to the accompanying drawing, forming a part thereof.

Fig. 1 is a perspective view of a casing for a motor vehicle heater or similar article showing my new design;

Fig. 2 is a side elevation thereof.

I claim:

The ornamental design for a motor vehicle heater casing or similar article as shown.

FRANK ACTON.
